UNITED STATES PATENT OFFICE.

JOHN W. CURRY, OF CINCINNATI, OHIO.

TRAFFIC-DIRECTING APPARATUS.

1,382,482.

Specification of Letters Patent. Patented June 21, 1921.

Application filed October 21, 1918. Serial No. 259,101.

To all whom it may concern:

Be it known that I, JOHN W. CURRY, a citizen of the United States, residing at Cincinnati, in the county of Hamilton and State 5 of Ohio, have invented certain new and useful Improvements in Traffic-Directing Apparatus, of which the following is a specification.

My invention relates to improvements in 10 apparatus to assist in the control of street traffic. One of its objects is to provide traffic signal apparatus and a post of observation for traffic officers, and supporting means therefor, all of which will be out of the way 15 and path of traffic, and advantageously placed for observation purposes. Another object is to provide an improved post of observation from which traffic signals may be directed and means to support the same. An- 20 other object is to provide an improved traffic signal apparatus and means to support and actuate the same. My invention also com- 25 prises certain details of form, combination and arrangement, all of which will be fully set forth in the description of the accom- 30 panying drawings, in which:

Figure 1 is a side elevation of my im- 35 proved apparatus in position for use.

Fig. 2 is a top plan view of the same.

Fig. 3 is a perspective detail of a portion 40 of the signal apparatus detached.

The accompanying drawings illustrate the preferred embodiment of my invention in which A and B respectively represent up- 45 right posts, preferably of metal, which are preferably set inside of the curb on diagonally opposite corners at the intersection of two streets K and L but may be placed on opposite sides of a street wherever traffic 50 regulating apparatus is required. The side- walks are represented by 3 and the curbs by 4, and the buildings by 5.

At a height sufficient to be above the heads 55 of pedestrians on the side-walk, and thus out of the way of wheeled and pedestrian traffic is mounted on one of the poles, say A, a platform or cage 6 to serve as a post of observation, and also as a housing and protection from extremely hot or cold weather 60 and storms for a traffic officer. Said housing is preferably of octagonal outline provided with eight windows 7, and affording an unobstructed view up and down both 65 streets and in all directions.

Above the cage 6, and of sufficient height 70

to pass above and clear of the usual electric trolley wires 8, 9, 10, and 11 forming a crossing at the intersection of the streets, is a strut or cross-bar 12, which connects the uprights A and B together, and is supported 60 thereon. Tie-rods 14 and 15 from the upper ends of the posts A and B to near the center of the cross-bar 12 are employed to give 65 rigidity to the structure and prevent sagging of the central portion of the cross-bar 12. The cross-bar 12 is preferably a light weight 70 channel bar attached at its ends to the posts A and B by means of angle brackets 16.

Vertically above the center of intersection 75 of the streets, and mounted on the cross-bar 70 12 is a vertical journal box 17 in which is journaled a shaft 18 to the lower end of 75 which are pivotally attached four signal arms 19. The pivotal movement of said arms relative to the shaft 18 is such that 80 the arms when in use occupy substantially horizontal positions, and are held by stop lugs 20 from falling below a horizontal position. When not under the control of a traffic officer the arms 19 are drawn up 85 against the sides of the shaft 18 to substantially vertical positions as indicated in dotted line in Fig. 3. Small wires or cable 21 attached to the ends of the signal arms and 90 leading over pulleys 22 and 23 to the ob- 95 servation cage enable the signal arms to be lifted to the vertical position when desired.

The shaft 18 is provided with stop lugs 24 to engage a stop on the cross-bar 12 to limit 95 the rotary movement of the shaft 18 to sub- 100 stantially one quarter of a revolution. The shaft 18 is provided with a crank arm 25 which is pivotally connected to one end of a link 26. The opposite end of the link 26 is pivotally connected to one end of a bell-crank 105 lever 27 which is pivotally attached to the cross-bar 12 above the observation cage. A link 28 is pivotally attached at one end to the opposite end of the bell-crank lever, and the opposite end of link 28 is pivotally at- 110 tached to one end of a hand lever 29. The hand lever is pivotally attached near its center to the post A within the cage. The traffic officer is thus enabled by movement of the hand lever to partially rotate the shaft 18 and expose the desired signals, say "Stop" and "Go" to traffic on either street.

The shaft 18 extends down through the central opening between the trolley wires so 110 that the signal arms are exposed to view be-

low the trolley wires, and at the same time the signal arms are out of the path of the trolley poles, and are in position to be readily seen by foot and wheel traffic, and without 5 out in any way obstructing traffic, or being in danger of being run down by carelessness on the part of vehicle traffic. Also the traffic officer instead of being located on the street level where it is often difficult for him to obtain 10 a comprehensive view of the traffic, and where he is in danger of being run down, is in an elevated position where he has a free and unobstructed view of the traffic in all directions, where he is not himself an obstruction to traffic, and where he is able to receive 15 protection from the weather.

The apparatus herein illustrated and described is capable of considerable modification without departing from the principle of 20 my invention.

What I claim is.

1. A traffic directing apparatus comprising a substantially vertical rigid support located at one side of a street, an elevated 25 rigid laterally projecting bar supported upon and at the upper end of said vertical member and overhanging the street, a vertically disposed signal shaft rotatably journaled in a bearing rigidly mounted upon

said laterally projecting bar at substantially 30 the center of the street, means carried by said laterally projecting bar to engage a member carried by said signal shaft to limit the rotary movement of said shaft, signal arms carried by said signal shaft, an observer's support carried at an intermediate position upon and by said vertical support, and elevated above the street to afford the observer an unobstructed view over pedestrians and vehicles, and means operable from 40 said observer's support to rotatably actuate said signal shaft.

2. A traffic directing apparatus comprising 45 a member stationarily and rigidly supported in an elevated position above a street intersection and provided with a vertically disposed shaft bearing, a vertically disposed shaft rotatably mounted in said shaft bearing, signal arms pivotally connected to said shaft and adjustable relative to said shaft 50 from substantially horizontal to substantially vertical positions, means to adjust said signal arms relative to said shaft, and means to rotatably move said shaft from a distant position.

In testimony whereof I have affixed my signature.

JOHN W. CURRY.
